UNITED STATES PATENT OFFICE.

THEODORE C. COOKE, OF SWAMPSOFT, MASSACHUSETTS.

GYRATORY CRUSHER.

Application filed October 27, 1927. Serial No. 229,076.

This invention relates to gyratory crushers for crushing or breaking rock or like materials in which crushers a shaft or pestle member is mounted for gyratory movement 5 within a crusher bowl or annular member into which the rock or other material is introduced in order to be crushed or broken between the crushing faces of the annular bowl and the exterior wall or surface of a 10 crusher head carried on the crusher shaft or pestle member.

The object of the present invention is to provide an improved crusher wherein the means for effecting the gyratory movement 15 of the crusher shaft within the crusher bowl is so constructed as to result in much greater operating efficiency and a maintenance of said efficiency without the disadvantages inherent in gyratory crushers now in commercial use. According to this invention 20 the gyratory movement of the crusher shaft is effected by means of a novel anti-friction or roller bearing eccentric device especially suited for crusher needs, efficiency and use. Efficiency in crushing, low maintenance and 25 continuity of operation are the principal advantages of crushers made in accordance with this invention. The frictional efficiency of roller bearings over the Babbitt 30 bearings is of course well known and lies mainly in the elimination of the heat developed in crusher eccentrics in crushers in use today. The elimination of rebabbitting which is necessary at least one or two times 35 a year on machines now in commercial use is an important item for it requires from one to twenty hundred pounds of expensive Babbitt or bearing metal. It is then also an object of the present invention to dispense 40 with rebabbitting and thus secure greater economy and continuity of operation, reliability of the crusher, and save shutdowns which constitute a serious hazard to the stone business in its short seasonal rush. In 45 addition to the frictional efficiency of this device it has a high efficiency of the crushing cavity itself. A slight loss of motion through wear at the eccentric bearing results in a loss in crushing efficiency in that 50 the crushing stroke or scope of movement of the shaft becomes less and less as the bearings wear. The crushing efficiency of machines containing a Babbitt eccentric, such as those now in current use, decreases steadily from the time it is started until its motion is substantially lost and its efficiency

is zero. Most machines in current use reach this point at least two or three times a year and the only remedy is rebabbitting, while the machine, hereinafter described, is not 60 subject to any appreciable loss in crushing efficiency in a similar period. Additional advantages of this crusher lie in the ease in which it may be lubricated and in the economy of oil, there being a reduction from 65 many barrels per year to a few gallons.

The foregoing then, describes the state of the practical commercial art, and though the patented prior art discloses various unused and impractical schemes for employing anti-friction bearings it does not disclose anything which effectually deals with the problems presented by the conditions above outlined nor a device having the novel features or advantages of a gyratory crusher made in accordance with this invention. 75

The invention is clearly illustrated in the accompanying drawings in which

Fig. 1 is a vertical sectional elevation of the preferred form of gyratory crusher 80 made in accordance with the invention, and Fig. 2 is a plan view (partly broken away) of that section of the crusher including the eccentric which lies below the irregular line 2, 2 looking with the arrows. 85

Referring to the drawings, the bowl or top shell, generally designated as 1, surrounds the shaft 2 carrying the head 3, the shaft in this preferred form being suspended by a nut 3^a from the spider 4 through which the shaft passes, though the shaft may be otherwise mounted for its gyratory movement. The lower end of the shaft 2 passes through the eccentric driving means, generally designated as 5. By this eccentric driving means an eccentric motion is imparted to the lower end of the shaft so that this lower end of the shaft moves in an orbit about the vertical axis of the machine. The eccentric driving means 5 is 90 suitably held in the bottom shell or frame 6 to which the bowl or top shell 1 and spider 4 are held by through bolts 6^a. The eccentric driving means 5, as here shown, consists of a bed-plate 7 suitably affixed to the frame 6 (by means not shown) which bed-plate embraces the entire eccentric driving means and contains a large annular race 8, keyed to the bed-plate 7. Within the race 8 is a set of anti-friction members such as 9 rolls 9 and within this outer set of rolls is 95 an annular member 10 having an eccentric 100

bore. To this ~~annular~~ member or eccentric ring 10 is affixed a bevel ring gear 11 for the purpose of driving the same, the bevel gear being held to the eccentric ring 10 for example by means of cap screws 12 and shear bushings 13. The eccentric ring 10 carries within its eccentric bore or race a second set of anti-friction members, such as the rolls 14 which rolls surround an annular member 15. This annular member is here shown as surrounding a cylindrical sleeve 16 placed upon the lower end of the shaft 2. This sleeve 16 may be omitted from the lower end of the shaft 2 so that the ring 15 contacts with the shaft 2 though I prefer to employ the sleeve and have the ring 15 bear against it. The ring 15 is here shown as having a frusto-conical or tapered bore which allows it to contact with the sleeve 16 throughout the full length of the tapered bore thus giving a long bearing on the sleeve 16. It is essential to the operation of this device that the lower end of the shaft be free to gyrate in an orbit about the vertical axis of the machine and in so doing it is always at an inclination to such vertical axis. This tapering of the ring 15 permits this gyration and at the same time provides the full length bearing against the sleeve 16 (or the shaft 2 if the sleeve be omitted) as before described. It will be seen that this gyratory movement could be accommodated by various other means, for example, by a cylindrical bore in the member 15 if the sleeve 16 were suitably tapered, or, both the sleeve 16 and the ring 15 might be tapered so long as the tapers were so made as to provide an adequate means to impart the thrust and permit the essential gyratory movement, and it is not intended to limit this portion of the invention to the precise means by which this free gyratory movement of the lower end of the shaft 2 is permitted. The lower diameter of the tapered aperture in the annular ring as shown is but slightly larger than the diameter of the shaft or the bushing to protect the shaft from wear while the upper diameter is just sufficient to allow the gyratory movement and still give a line of contact throughout the length of the taper.

As before mentioned the intermediate or eccentric ring 10 has attached to it the ring gear 11. This ring gear 11 is driven through the beveled gear pinion 17 affixed to the shaft 17^a to which the power is applied. This ring 10 has its outer circumference concentric with the ring or race 8 and bears to it through the outer circle of rolls 9. The inner diameter or eccentric bore of the ring 10 bears against the inner set of rolls 14 to the inner ring 15 and thence to the shaft 2 through the sleeve 16 by means of the tapered bore of the ring 15, as above described, which permits the gyra-

tory movement. Hence as the intermediate or eccentric ring 10 is driven through its cycle it imparts a gyratory motion to the lower end of the shaft 2 as is typical of gyratory crushers now in use and the crushing action in the crushing cavity between the head 3 and the replaceable concave crushing plates 1^a carried within the bowl 1 is likewise typical of gyratory crushers in common use today.

The weight and wear from the weight of the moving parts of the eccentric bearing is taken by the replaceable wearing ring 18. The cover plate 19 overlying the ring 15, roll members 14, and a portion of the eccentric ring 10 is affixed to the latter by means of being held between the ring gear 11 and the ring 10 as plainly shown in Fig. 1, thus this plate rotates with the intermediate ring 10 and throws outwardly by reason of centrifugal force any particles of grit, metal, or the like, that might fall upon it so that such particles are thrown over the gear 11 and deposited outside of the ring 8 in the annular cavity 20 and can not enter the bearing itself. Lubrication of the bearing is had by oil poured into the reservoir 21 to a level nearly overflowing the outer race 8. When the machine is running some of the oil is thrown by centrifugal force to the outer diameter of the bearing cavity 20. It then flows around the bed-plate 7 on the outside of the outer ring 8 to the pipes 22 and thence by gravity to the lower part of the sump 23 which may be provided with a drain plug (not shown) through which sediment water or oil may be drawn.

The preferred structure, its mode of operation, and the advantages attendant thereto, will be evident from the above description and having described my invention, I claim:

1. A gyratory crusher having, in combination, a crusher bowl, a shaft and crusher head mounted for gyratory movement, an anti-friction eccentric driving means adapted to impart a gyratory motion to said shaft and crusher head, said eccentric driving means including an outer race, a set of anti-friction members adapted to cooperate with said outer race, an intermediate member adapted to cooperate with said set of anti-friction members, said intermediate member having an eccentric bore, means to rotate said intermediate member, a second set of anti-friction members adapted to cooperate with said eccentric bore, and means separate from said shaft cooperating with the inside of said second set of anti-friction members adapted to tip the shaft with respect thereto and adapted to permit and to impart a gyratory movement to said shaft.

2. A gyratory crusher having, in combination, a crusher bowl, a shaft and crusher head mounted for gyratory movement, an

anti-friction eccentric driving means adapted to impart a gyratory motion to said shaft and crusher head, said eccentric driving means including an outer race, a set of anti-friction members adapted to cooperate with said outer race, an intermediate member adapted to cooperate with said set of anti-friction members, said intermediate member having an eccentric bore, means to rotate said intermediate member, a second set of anti-friction members adapted to cooperate with said eccentric bore, and an inner ring with a frusto-conical bore adapted to impart and permit a gyratory movement of said shaft.

3. A gyratory crusher having, in combination, a crusher bowl, a shaft and crusher head mounted for gyratory movement, an anti-friction eccentric driving means adapted to impart a gyratory motion to said shaft and crusher head, said eccentric driving means including an outer race, a set of anti-friction members adapted to cooperate with said outer race, an intermediate member adapted to cooperate with said set of anti-friction members said intermediate member having an eccentric bore, means to rotate said intermediate member, a second set of anti-friction members adapted to cooperate with said eccentric bore, and an inner member having its axis parallel with the axis of the crusher, oblique to the axis of said shaft, and being adapted to impart and permit a gyratory movement of said shaft.

4. A gyratory crusher having, in combination, a crusher bowl, a shaft and crusher head mounted for gyratory movement, a sleeve mounted on the lower end of said shaft, and anti-friction eccentric driving means adapted to impart a gyratory motion to said shaft and crusher head, said eccentric driving means including an outer race, a set of anti-friction members adapted to cooperate with said outer race, an intermediate member adapted to cooperate with said set of anti-friction members said intermediate member having an eccentric bore, means to rotate said intermediate member, a second set of anti-friction members adapted to cooperate with said eccentric bore, and means separate from said shaft cooperating

with said second set of anti-friction members adapted to tip the shaft with respect thereto and adapted to permit and to impart a gyratory movement to said shaft. 55

5. A gyratory crusher having, in combination, a crusher bowl, a shaft and crusher head mounted for gyratory movement, an anti-friction eccentric driving means adapted to impart a gyratory motion to said shaft 60 and crusher head, said eccentric driving means including an outer race, a set of anti-friction members adapted to cooperate with said outer race, an intermediate member friction members, said intermediate mem- 65 frition members, said intermeditate mem-ber having an eccentric bore, means to ro-tate said intermediate member, a second set of anti-friction members adapted to co-operate with said eccentric bore, means sep- 70 arate from said shaft cooperating with said second set of anti-friction members adapted to tip the shaft with respect thereto and adapted to permit and to impart a gyratory movement to said shaft, and means on the 75 bed plate of said crusher adapted to support said sets of anti-friction members, and said intermediate member, and said last men-tioned means.

6. A gyratory crusher having, in com-bination, a crusher bowl, a shaft and crusher head mounted for gyratory movement, an anti-friction eccentric driving means adapted to impart a gyratory motion to said shaft 80 and crusher head, said eccentric driving 85 means including an outer race, a set of anti-friction members adapted to cooperate with said outer race, an intermediate member adapted to cooperate with said set of anti-friction members, said intermediate member 90 having an eccentric bore, means to rotate said intermediate member, a second set of anti-friction members adapted to cooperate with said eccentric bore, covering means over said sets of anti-friction members, and an 95 inner member having its axis parallel with the axis of the crusher, oblique to the axis of said shaft and being adapted to impart and permit a gyratory movement of said shaft.
